UNITED STATES PATENT OFFICE

104,257

DESIGN FOR A COMBINED CONSTELLATION FINDER AND FLASHLIGHT HOLDER

Albert Y. Hayes, San Antonio, Tex.

Application February 13, 1937, Serial No. 67,659

Term of patent 3½ years

To all whom it may concern:

Be it known that I, Albert Y. Hayes, a citizen of the United States, residing at San Antonio, in the county of Bexar and State of Texas, have invented a new, original, and ornamental Design for a Combined Constellation Finder and Flashlight Holder, of which the following is a specification, reference being had to the accompanying drawing, forming part thereof.

Fig. 1 is a front elevational view of a combined constellation finder and flashlight holder showing my new design;

Fig. 2 is a side elevational view;

Fig. 3 is a sectional view, on line 3—3 of Fig. 1; and,

Fig. 4 is a top plan view.

I claim:

The ornamental design for a combined constellation finder and flashlight holder, substantially as shown.

A. Y. HAYES.
